UNITED STATES PATENT OFFICE.

BENJAMIN N. WELLS, OF RALEIGH, NORTH CAROLINA, ASSIGNOR TO THE SEAMLESS CAN & BUCKET CO., OF BALTIMORE, MARYLAND, A CORPORATION OF MARYLAND.

DISPENSING VESSEL.

Application filed April 18, 1922. Serial No. 554,884.

To all whom it may concern:

Be it known that I, BENJAMIN N. WELLS, a citizen of the United States, residing at Raleigh, in the county of Wake and State of 5 North Carolina, have invented certain new and useful Improvements in Dispensing Vessels, of which the following is a specification.

This invention relates to an attachment 10 for cans or other closed vessels of the type having a pouring spout and a vent tube controlled by valves. In the present invention, the vent tube and the spout are normally closed at their inner ends by ball valves, 15 which valves roll from their seats when the can is tilted from the upright to the pouring position and roll back to their seats when the can is brought back to its upright position. Such cans are particularly desirable 20 as containers for the more volatile liquids, such as benzine or gasoline, as the valves are always closed when the can is in upright position, and hence no loss occurs through the escape of vapors from the vessel. If the 25 can is tipped over accidentally, however, the contents will run out through the spout unless some means is provided for holding the ball valve in the spout against its seat. I therefore provide a simple and inexpensive 30 attachment in the spout whereby the ball valve in the spout may be locked against its seat, to prevent the spilling of the can contents, which attachment is accessible at the outer end of the spout and may be adjusted 35 to release or lock the ball. This attachment comprises a rod movable longitudinally in the spout and having means at one end for yieldingly engaging the ball, and means at its opposite end for engaging the spout to 40 lock the attachment in either its inner or outer position.

In the accompanying drawing,

Fig. 1 is a central vertical section through the upper portion of a can equipped with my 45 improvements, the can being shown in upright position;

Fig. 2 is a similar view, showing the can tilted into position to pour out its contents;

Fig. 3 is a section on the line 3—3 of Fig. 50 1; and,

Fig. 4 is a side elevation of the locking rod for the valve.

Referring to the drawing, α represents a can body having a closed top α' , and α^2 indicates a pouring spout secured to the top of

the can. A vent tube b extends parallel to the spout and preferably extends slightly beyond the outer end of the latter, as shown. This tube extends through the top of the can and then along the underside of the top 60 to a point diametrically opposite the spout. The inner side of the vent tube extends into a box-like valve casing 1, having an opening or port 2 in its lower side, which port is closed by a ball valve 3 when the can is in 65 the upright position shown in Fig. 1. When the can is tilted to pour its contents out through the spout, the valve 3 rolls out of the seat 2 toward the end of the vent tube. In order to prevent the ball from closing the 70 vent tube, a pin 4 is arranged in the valve casing immediately in front of the end of the tube.

The top of the can is formed with an opening or port 5, which is surrounded by the 75 spout, and a ball valve 6 closes this port when the can is in the upright position, as shown in Fig. 1, and is adapted to roll out of the port when the can is inclined, as 80 shown in Fig. 2.

These ball valves, it will be evident, will prevent vapors arising from volatile liquids in the can from escaping to the atmosphere when the can is in upright position. When the can is tilted to pour out its contents, both 85 valves will leave their seats and the liquid will pour out of the spout while air will flow into the can through the vent tube. If the can spout and the end of the tube are inserted in a vessel into which the liquid is being 90 poured, it will be evident that when the liquid reaches the height of the spout and tube, the flow of liquid will stop because the vent tube as well as the spout will be closed by the 95 liquid in the receiving vessel.

It is desirable when the cans are used for shipping or storing the liquid, or when they are used in places where they are liable to be tipped over, to have means for locking the valve in the spout so that the can contents will not escape, if such accident occurs. I have provided a simple and inexpensive attachment c , for locking and unlocking the ball valve in the spout, consisting of a rod composed of several strands of spring wire 105 7, 8, 9, which are soldered or brazed, or otherwise secured together throughout the greater portions of their lengths but separated near one end, as shown at 7 a , 8 a , and 9 a , to form a resilient end for engaging the 110

valve, and one of the wires, as 9, is extended beyond the others at the opposite end and bent over at right angles to form an arm 9^b, the extremity of which is turned backward 5 parallel with the wire 9 to form a hook 9^c. A flat narrow supporting strip 10 extends across the interior of the spout at a distance from the ball valve greater than the length of the feet 7^a, 8^a, 9^a, and the rod *c* extends 10 freely through an opening 10^a in the strip 10. The outer end of the pouring spout is provided at one side with a bayonet slot 11, adapted to receive the right-angled arm 9^b of the rod *c*.
15 When the can is not in use, the rod *c* is pressed inward against the ball 6 and the arm 9^b engages the bayonet slot 11 and thereby the rod is locked against longitudinal movement and the spring feet 7^a, 8^a and 9^a
20 press the ball against the valve seat. When it is desired to pour liquid from the can, the operator by taking hold of the arm 9^b, which is accessible at the outer end of the spout, moves the arm into alinement with the part 25 11^a of the bayonet slot and then pulls outwardly on the rod, thus lifting the feet 7^a, 8^a and 9^a out of engagement with the ball. As the rod is pulled outward, these spring arms or feet engage the wall of the opening 30 10^a and limit the distance to which the rod may be pulled outwardly. To lock the rod in the pouring position, the operator swings the arm 9^b across the end of the vent tube and the hooked end 9^c of the rod enters the 35 tube and thereby locks the rod in its outer position. While the rod is thus secured, the ball is free to roll into or out of the port 5 as the can is moved between the pouring and the upright positions. When the operator is 40 through pouring the liquid, he again brings the can to the upright position and then unhooks the rod from the end of the vent tube and presses the arm 9^b into the bayonet slot, thereby locking the ball valve 6 in position to close the port and prevent spilling of the contents in case the can is tipped over.

What I claim is:

1. The combination with a vessel having a top provided with an opening and a spout 50 on the top surrounding said opening, of a ball adapted to seat in said opening when the

vessel is upright and to roll from its seat when the vessel is tilted, and means for holding said ball on its seat comprising a rod extending into the spout and having a 55 resilient end adapted to bear against the ball, said rod being adjustable longitudinally of the spout to lock and release the ball.

2. The combination with a vessel having a top provided with an opening and a spout 60 on the top surrounding said opening, of a ball adapted to seat in said opening when the vessel is upright and to roll from its seat when the vessel is tilted, and means for holding said ball on its seat comprising a 65 rod having a resilient end adapted to bear against the ball and extending to the outer end of the spout, said rod being movable longitudinally of the spout and having means for engaging the spout to lock the 70 rod in its inner position.

3. The combination with a vessel having a top provided with an opening and a spout on the top surrounding said opening, of a ball adapted to seat in said opening when the 75 vessel is upright and to roll from its seat when the vessel is tilted, and means for holding said ball on its seat comprising a rod having resilient forked arms at one end adapted to engage the ball, said rod extending to the outer end of the spout and having a laterally extending arm at its outer end, and said spout having a bayonet slot adapted to receive said laterally extending 80 arm. 85

4. The combination with a vessel having a top provided with an opening and a spout on the top surrounding said opening, of a ball adapted to seat in said opening when the vessel is upright and to roll from its seat 90 when the vessel is tilted, and means for holding said ball on its seat comprising a rod having resilient forked arms at one end adapted to engage the ball, said rod extending to the outer end of the spout and having a laterally extending arm at its outer end, said spout having a bayonet slot adapted to receive said laterally extending arm and a cross bar in the spout having a guide opening 95 through which said rod extends.

In testimony whereof I affix my signature
BENJAMIN N. WELLS.
